LEOPOLD BERTSCHE, JR., OF ALLEGHENY CITY, PENNSYLVANIA.

Letters Patent No. 91,597, dated June 22, 1869.

FIRE-PLACE GRATE.

The Schedule referred to in these Letters Patent and making part of the same.

To all whom it may concern:

Be it known that I, LEOPOLD BERTSCHE, Jr., of Allegheny City, in the county of Allegheny, and State of Pennsylvania, have invented a new and useful Improvement in Fire-Grates; and I do hereby declare that the following is a full, clear, and exact description thereof, which will enable others skilled in the art to make and use the same, reference being had to the accompanying drawing, forming part of this specification, in which—

Figure 1 is a vertical cross-section of my improved grate, taken through the line $x-x$, fig. 2.

Figure 2 is a plan view of the same, part being broken away to show the construction.

Similar letters of reference indicate corresponding parts.

My invention has for its object to furnish an improved fire-grate, which shall be so constructed and arranged that the bars, when burned out, can be conveniently taken out singly, and replaced with new ones; and

It consists in the detachable grate-bars, constructed substantially as herein shown and described, in combination with the cross and side-bars, in the manner set forth.

A is the top cross-bar of the grate, which is formed with round tenons upon its ends, which pass through holes in the upper end of the side-bars B, and are secured in place by pins, or other conveniently-detachable means.

C is the lower cross-bar, upon the ends of which are formed round tenons, which pass through holes in the lower ends of the side-bars B, where they are secured in place by pins, or other conveniently-detachable means.

D are the grate-bars, upon the upper ends of which are formed cross-heads, d' , which enter a longitudinal groove formed in the upper bar A, and the body of which enters a transverse notch formed in the said cross-bar A.

The lower ends of the grate-bars D enter and rest in notches formed in the lower cross-bar C, as shown in figs. 1 and 2.

By this construction, by turning the lower cross-bar D, the bars C may be taken out and replaced with new ones. Should there be occasion, the side-bars B may be readily detached by removing the pin or pins by means of which they are secured in place.

Having thus described my invention,

What I claim as new, and desire to secure by Letters Patent, is—

The grate-bars D, constructed with cross-heads d' , in combination with the upper bar A, lower bar C, and detachable side-bar B, said parts being constructed, arranged, and operating substantially as herein shown and described, and for the purpose set forth.

LEOPOLD BERTSCHE, JR.
